J. Stuart Freeman,

Attorney

UNITED STATES PATENT OFFICE

JOHN GALLAGHER, OF PHILADELPHIA, PENNSYLVANIA

ADVERTISING DEVICE

Application filed January 29, 1931. Serial No. 512,088.

The object of the invention is to provide improvements in advertising devices, and particularly in that class which comprises movable, illuminated display means.

Another object is to provide a rotatable member, carrying a series of advertisements (or in fact other information if desired), and means for electrically illuminating the advertisements of said series periodically, as they are presented to view in sequence.

A further object is to provide such a device with means to adapt such a device to operation by the waves of the sea, and to provide for insuring a predetermined movement of the device even when waves of but low amplitude are available, and to limit such movement at the proper point to insure a display of each advertisement in the desired direction.

With the objects of the invention thus broadly stated, the invention comprises further novel details of construction and operation, which are fully brought out in the following description, when read in conjunction with the accompanying drawings, in which Fig. 1 is a front elevation of one embodiment of the invention; Fig. 2 is an end elevation of the upper portion of the same; Fig. 3 is a vertical section of the same; and Fig. 4 is a detail showing the cam structure which insures the proper length of movement and position at which the display portion of the device shall stop following each wave impulse.

Referring to the drawings, the platform portion of a pier 1 or other suitable fixed support is shown as being provided with a bracket 2, which serves as a pivotal support for an oscillatory member 3. To this member is pivotally secured at 4 a depending rod 5, to the lower end of which is secured any desired form of float 6, while a link 7 is pivotally secured both to the under side of said support at 8 and to said rod at 9.

Rising vertically from the upper surface of said support are two or more standards 10, through the upper portions of which is journaled a shaft 11, to which is suitably secured a cam 12, having regularly spaced, relatively abrupt depressions 13, from which the radial

outer cam surface is abruptly curved (radially outwardly) at 14 and thence merges into and gradually through a surface section 15 towards and into the next adjacent depression 13. Pivotaly mounted upon one of the standards 10 is a spring-pressed lever 16, having a roller or other anti-friction means 17 upon its free end, adapted to continuously engage said cam surface, and by virtue of the spring 18 tend to rotate the cam 12 into such position that the member 17 will always move into one of the depressions 13 and at that point cause the cam and shaft 11 to cease rotating. Thereafter a slight additional movement of the shaft 11 rotates the cam 12 again in the direction of the arrow shown in Fig. 4, so that the anti-friction member 17 rises up and over the next adjacent abrupt curvature 14, after which, if the initial force applied to said shaft ceases, the spring 18 acting against the adjacent lever will again force the member 17 radially inwardly and the cam angularly, until said member 17 has again entered a depression 13. This construction is particularly valuable to recommend the device for regular operation when there is only available the usual irregular force characterizing the motion of the waves of the sea, with the result that whether the vertical oscillations of the float 6 as caused by such waves are of great or short amplitude, the illuminated advertising device hereinafter described will always come to rest in one of several predetermined positions.

The shaft 11 is additionally provided with a ratchet wheel 19, which is engaged by a spring-pressed pawl 20, carried by a collar 21 rotatably mounted upon said shaft, and to which is pivotally connected at 22 a rod 23, which connects said collar with any desired adjustable point 24 upon the oscillatory member 3, said oscillatory member being provided with an adjustable weight 25 which serves to counterbalance the dead weight of the float 6 and supporting rods.

The advertising portion of the device per se comprises a star-shaped frame embodying radially extending opaque partitions 26, separating compartments in which are positioned electric lamps 27, said compartments being

closed radially outwardly by means of any desired form of transparent or partly transparent material 28, such as glass or the like, upon which may be painted, or otherwise applied, letters or other advertising indicia 29, such as shown in Fig. 1. Means for illuminating the lamps 27 in each of the said compartments independently but throughout a predetermined portion of their path of rotation may comprise any suitable form of commutator, such as a series of segments 30, carried by or at least rotatable with the shaft 11 and cam 12, against which commutator segments presses a brush 31, which is diagrammatically represented in Fig. 4 and which may be electrically connected in any well-known manner to a source of electric power while the various segments 30 are similarly connected to the lamp or series of lamps 27 in the respective compartments as shown in Fig. 3.

Having thus described my invention, what I claim and desire to protect by Letters Patent of the United States is:

1. A display device, comprising a rotary member having compartments separated from one another by opaque partitions, electric illuminating means within said compartments, a pivotally mounted oscillatable member, a float connected to said oscillatable member, and a ratchet and link unit connecting said oscillatory and rotary members together, and operative when said float rests upon sea waves to cause intermittent movement of said first-named member.
2. A display device, comprising a rotary member, oscillatory means of varying amplitude to rotate said member, a cam carried by said member and having regularly spaced radially positioned surface portions approached by surfaces of radial variation, and means engaging said cam and actuated by said oscillatory means, whereby movements of different degrees by said oscillatory means will result in uniform movements by said member.
3. A display device, comprising a rotary member having compartments, electric illuminating means within said compartments, means covering said compartments adapted to carry indicia and to pass light rays from said first means, a cam carried by said member, means engaging said cam to insure said rotary member stopping at predetermined intervals during intermittent rotation, driving means, and a connection between said driving means and said rotary member.
4. A display device, comprising a rotary member having compartments, electric illuminating means within said compartments, means covering said compartments adapted to carry indicia and to pass light rays from said first means, a cam carried by said member, means engaging said cam to insure said rotary member stopping at predetermined intervals during intermittent rotation, an oscillatory member, a float carried thereby and

adapted to engage sea waves, and a ratchet and link connection between said last-named member and said first-named member to transmit motion from one to the other.

5. In a device of the class described, a fixed support, a member pivotally carried thereby, a float, a link connection between said float and said member, and a radius rod connecting said float with said fixed support, to limit the motion of said float to a predetermined path.

6. In a device of the class described, a fixed support, a member pivotally carried thereby, a float, a link connecting said float to said member, an adjustable weight carried by said member to counterbalance the dead weight of said float, and a radius rod connecting said float with said fixed support, to limit the motion of said float to a predetermined path.

In testimony whereof I have affixed my signature.

JOHN GALLAGHER.
